(57) CLAIM

The ornamental design for a massage device, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top perspective view of a massage device.

FIG. 2 is a bottom perspective view of the massage device.

FIG. 3 is a front elevation view of the massage device.

FIG. 4 is a top plan view of the massage device.

FIG. 5 is a bottom plan view of the massage device.

FIG. 6 is a left side elevation view of the massage device.

FIG. 7 is a right side elevation view of the massage device.

FIG. 8 is a rear elevation view of the massage device; and, FIG. 9 is a cross sectional view along line 9-9 shown in FIG. 4.

The broken lines shown in the drawings are for illustrative purposes only and form no part of the claimed design.
